FOLDING POCKET HACK SAW

Gifford Allen, Grand Junction, Colo.

Application June 27, 1941, Serial No. 399,999

5 Claims. (Cl. 145—33)

This invention relates to a folding pocket hacksaw, and has for its principal object the provision of a hacksaw frame which will be exceedingly strong and rigid when in use, and which can be quickly and easily folded into a small, compact article when not in use so that it may be conveniently carried in the pocket.

Another object of the invention is to provide highly efficient and positive means for attaching the hacksaw to its supporting frame.

Other objects and advantages reside in the detail construction of the invention, which is designed for simplicity, economy, and efficiency. These will become more apparent from the following description.

In the following detailed description of the invention reference is had to the accompanying drawings which forms a part hereof. Like numerals refer to like parts in all views of the drawings and throughout the description.

In the drawings:

Fig. 1 is a side view of the improved folding hacksaw illustrating it in the open position ready for use;

Fig. 2 is a fragmentary sectional view of the handle portion thereof; this section is taken on the line 2—2, Fig. 3;

Fig. 3 is a front end view thereof;

Fig. 4 is a detail view of the saw tightening block employed in the improved saw;

Fig. 5 illustrates the handle portion of the device with the side pad, side plate and knife sheath removed illustrating it as it would appear when folded for carrying;

Fig. 6 is a similar view illustrating the sheath in place and the hacksaw blade in place therein;

Fig. 7 is a longitudinal section through the handle, taken on the line 7—7 Fig. 6, with the blade and supporting arm removed.

Fig. 8 is a detail cross-section taken on the line 8—8 Fig. 6; and

Fig. 9 is a detail cross-section taken on the line 9—9 Fig. 5.

The improved hacksaw comprises a metal handle form 10, closed at each side by means of relatively thin side plates 11. The side plates are covered with hand grip pads 35. The handle form is provided with an inclined receiving socket 43 extending throughout its length and opening at the top thereof. A blade-supporting bracket 12 projects from the front edge of the handle form 10. The socket 43 is designed to slidably receive a blade arm 13. The arm is provided with a hook member 15 which engages a stop pin 14 as the arm is withdrawn. The stop pin acts

as a pivot about which the arm swings to its operative position.

The inner extremity of the arm contains a notch 16 into which a latch member 17 extends to hold the arm 13 in the extended position. The latch is constantly urged toward the notch 16 by means of a leaf spring 18. The latch is mounted at one extremity upon a pivot pin 19 and is provided at its other extremity with a finger nob 20. 5 The nob projects through a slot 21 in one of the side plates 11, so that it is conveniently reached by the finger of the operator. The two side plates 11 and the grip pads are held in place on each side of the handle form 10 by means of 10 suitable rivets or screws 22.

The outer extremity of the arm 13 is provided with a hinged saw engaging member 23 mounted on the arm by means of a hinge pin 24. The member 23 is held at a predetermined angle 20 from the arm 13 by means of a hooked latch member 25 which is in turn mounted on a latch pin 26 on the arm 13. The hook of the latch member 25 engages in a suitable receiving notch 36 in the saw engaging member 23 to hold it 15 at its fixed angle.

A typical hacksaw blade is illustrated at 27 of any usual standard type having pin openings in its ends. At its outer extremity the blade 27 slips into a receiving slot in the free extremity 30 of the saw engaging member 23 and a locking pin 28 is inserted through the opening in the outer end of the blade. The locking pin is carried in a swinging hinged member 29 which is pivoted on the member 23 so that it may be swung 35 to one side to release the blade 27.

The other extremity of the blade is detachably secured in a sliding member 30 mounted in the blade bracket 12. The sliding member is split at its outer extremity to receive the blade 27 and 40 is longitudinally grooved along its top and bottom to form a V-shape, guide groove 32 to guide it into the bracket 12. The bracket is provided with a receiving slot for the member 30 and the parallel side edges of the slot are ridged to enter the groove 32 as shown in Fig. 9. The sliding member is moved back and forth by means of a threaded shaft 33 which projects from the member 30 into a receiving pocket in the handle form 10. The shaft 33 extends through a knurled nut 34. The nut 34 carries a flanged hub 31 which engages in notches in the form 10 to prevent axial movement of the nut. Therefore by rotation of the latter the saw blade may be placed under tension. The member 30 carries a hinged tab 37 having a blade pin 38. The tab 37 is indented

in the side of the member 30 and when it is closed the pin 38 extends through the pin hole in the end of the blade 27.

A relatively flat channel member or sheath 39 is secured on the outer face of one of the side plates 11, the handle pad 35 at that side being internally grooved to surround the sheath. The sheath is for receiving the saw blade when not in use. The sheath is provided with a longitudinally extending front bar 40 against which the teeth of the saw may rest. Ears 41 project from the sheath to secure the bar 40 in place and to engage the screws 22 to hold the sheath in place. It will be noted that the sheath is spaced from the bar 40 to allow the side set in the saw teeth to project. The entrance opening of the sheath may be split as shown at 42 to allow the upper edge to frictionally engage the saw to prevent it from falling from place.

When it is desired to fold the saw the nut 34 is loosened, the hinged members 29 and 37 are opened to release the blade 27 from its pins 28 and 38. The latch 25 is then released and the member 23 is folded against the arm 13. The latch 17 is then released and the outer extremity of the blade arm is raised so that its inner extremity may be slid into the receiving socket 11 as shown in Figure 5. The blade 27 is then inserted in the sheath 39 to form a compact unit of minimum size which may be easily carried in the pocket.

While the invention has been described as particularly applicable to a pocket hacksaw, it is not, of course, limited to this specific use as it will be found valuable with any type of saw and in any size to which such a construction can be applied.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A folding hacksaw comprising: a handle member having a longitudinally extending socket; an arm member slidably mounted in said socket so that it may be slid lengthwise into or withdrawn from said socket; means for limiting the extent of withdrawal of said arm, said latter means serving as a pivot to allow the arm to be turned to a pre-set projected position; a latch member in said handle member engaging said arm in the latter position to lock the same in place; a saw engaging member extending from the outer extremity of the arm to a position opposite the handle member; and means for securing a saw blade between the saw engaging member and the handle member.

2. A folding hacksaw comprising: a handle member having a longitudinally extending tubular socket; an arm member slidably mounted in said socket so that it may be slid lengthwise into or withdrawn from said socket; means for limiting the extent of withdrawal of said arm, said latter means serving as a pivot to allow the arm to be turned to a pre-set projected position; a latch member in said handle member engaging said arm in the latter position to lock the same in place; a saw engaging member extending from the outer extremity of the arm to a position

opposite the handle member; a latch member engaging said saw engaging member when the latter is turned to a predetermined angle; and means for securing a saw blade between the saw engaging member and the handle member.

3. A folding frame for hacksaws comprising: a handle member; a tubular receiving socket extending longitudinally within said handle member and opening to one extremity thereof; a blade arm freely slidable lengthwise of said socket and projecting from the open extremity thereof; a hook member adjacent the inner extremity of the forward edge of said blade arm; a pivot pin adjacent the open extremity of said socket in the path of said hook member to be engaged by the latter to limit the withdrawal of and to serve as a pivot for said arm to allow the latter to be swung forwardly from the axis of said socket; and a blade supporting member hingedly mounted on the outer extremity of said arm so as to project downwardly therefrom forwardly of said handle member, said frame being adapted to support a saw blade between the opposed free ends thereof.

4. A folding frame for hacksaws comprising: a handle member; a tubular receiving socket extending longitudinally within said handle member and opening to one extremity thereof; a blade arm freely slidable lengthwise of said socket and projecting from the open extremity thereof; a hook member adjacent the inner extremity of the forward edge of said blade arm; a pivot pin adjacent the open extremity of said socket in the path of said hook member to be engaged by the latter to limit the withdrawal of and to serve as a pivot for said arm to allow the latter to be swung forwardly from the axis of said socket; a blade supporting member hingedly mounted on the outer extremity of said arm so as to project downwardly therefrom forwardly of said handle member, said frame being adapted to support a saw blade between the opposed ends thereof, a latch member positioned to engage the inner extremity of said arm when the latter is rotated about said pivot pin to maintain said arm in its angular position; and means on the exterior of said handle member operatively connected with said latch member to release the latter from engagement with said arm.

5. A folding frame for hacksaws comprising: a handle member; a tubular receiving socket extending longitudinally within said handle member and opening to one extremity thereof; a blade arm freely slidable lengthwise of said socket and projecting from the open extremity thereof; a hook member adjacent the inner extremity of the forward edge of said blade arm; a pivot pin adjacent the open extremity of said socket in the path of said hook member to be engaged by the latter to limit the withdrawal of and to serve as a pivot for said arm to allow the latter to be swung forwardly from the axis of said socket; a blade supporting member hingedly mounted on the outer extremity of said arm so as to project downwardly therefrom forwardly of said handle member, said frame being adapted to support a saw blade between the opposed ends thereof and a sheath in said handle member parallel with said socket for receiving said blade when the latter is not in use.
